RAILWAY SIGNALING

George R. Pflasterer, Swissvale, Pa., assignor to
The Union Switch & Signal Company, Swiss-
vale, Pa., a corporation of Pennsylvania

Application April 14, 1936, Serial No. 74,257

25 Claims. (Cl. 246—50)

My invention relates to railway signaling, and particularly to signaling involving wayside signals for stretches of single track over which traffic moves in both directions.

- 5 A feature of my invention is the provision of novel and improved apparatus whereby, when the stretch is occupied by a train, the signals governing traffic following such train will provide a three-block, four-indication, system of signaling but whereby the signals governing traffic opposing such train will all display the stop indication. The apparatus provided by this invention is an improvement on that shown and claimed in an application of Henry S. Young, Serial No. 15 16,002, filed February 27, 1936, for Railway signaling.

- I will describe one form of apparatus embodying my invention, and will then point out the novel features thereof in claims. 20 In the accompanying drawings, Figs. 1A and 1B are diagrammatic views which, when placed end to end in the order named, illustrate one form of railway signaling system embodying my invention. 25 Similar reference characters refer to similar parts in each of the two views.

Referring to the drawings, the reference characters 7 and 8 designate the rails of a stretch of railway track over which traffic normally moves in both directions, which track is provided with two passing sidings P1 and P2. The stretch of track between these two sidings is divided by means of insulated joints 9 into a plurality of successive track sections W—X, X—Y, and Y—Z. 30 As here shown, each track section is divided into at least two subsections 1T, 2T, 3T, 4T, etc. Each subsection is provided with a track circuit comprising a track battery 10 connected across the rails at one end of the subsection, and a track relay, designated by the reference character TR with a prefix the same as the numerical prefix in the reference character of the associated subsection, connected across the rails adjacent the other end of the subsection. 35

40 Eastbound traffic, that is, traffic from left to right over the stretch of track shown in the drawings, is controlled by trackway signals 11, 13, 15, and 17, located at points W, X, Y, and Z, respectively. I shall term the signals 11 and 17 “headblock signals” and the signals 13 and 15 “intermediate signals”. 45

These signals each comprise an upper unit U and a lower unit L. As here shown, each upper unit U includes a red and yellow as well as a

green lamp and each lower unit L includes a single yellow lamp.

Each signal is controlled by a polarized direct current relay and by a neutral direct current relay designated by the reference characters H and J, respectively, each with a prefix the same as the reference character of the associated signal.

Each relay H is directly connected to a pair of line conductors each of which extends to the signal next in advance and each of which includes a front contact of each of the associated track relays.

Each relay J is directly connected to the output terminals of an asymmetric unit designated 15 by the reference character Q with a prefix the same as the reference character of the associated signal.

The input terminals of each asymmetric unit Q are connected, by means of front neutral contacts 20 of the associated relay H, to the same pair of conductors to which the relay H is connected, and are connected by means of back neutral contacts of the associated relay H, to the pair of conductors through a transformer and resistor 25 designated by the reference characters M and F, respectively, each with a prefix the same as the reference character of the associated signal.

It will be seen, therefore, that when the relays H are energized, the associated relay J also will 30 be energized but that the relays J may be energized independently of the energization of the associated relay H.

As will be explained more in detail hereinafter, each pair of conductors is at times supplied with 35 direct current and at other times supplied with alternating current. The high impedance of the direct current relays H will prevent the flow of alternating current in these relays so that the relays H will not respond when the line conductors are supplied with alternating current. The resistors F will prevent the excessive flow of direct current in the primary windings of the transformers M.

Associated with each intermediate signal and 45 controlled by the associated relay J, as well as the track relay for the subsection immediately in advance of the signal, is a directional stick relay designated by the reference character S with a prefix the same as the reference character of 50 the associated signal.

The relays H, J, and S control the energy supplied to the line conductors for the control of the relays H and J associated with the signal next in rear in such a manner that such conductors 55

will be supplied with direct current of normal polarity or with direct current of reverse polarity, or with alternating current or with no current, depending upon traffic conditions in advance.

5 Associated with each signal is a suitable source of direct current, the terminals of which are designated by the reference characters B and C.

10 Each signal is provided with a transformer, designated by the reference character N with a prefix the same as the reference character of the associated signal. Each transformer N includes a primary winding 19 and a secondary winding 20. The secondary winding 20 is at times connected to the line conductors extending in rear of the signal with which such transformer 15 is associated so that, when alternating current is supplied to primary winding 19, the relay J for the signal next in rear will become energized.

For supplying alternating current to the primary winding 19 of the transformers N, each 20 signal is provided with a device for converting direct current into alternating current and designated by the reference character A with a prefix the same as the reference character of the associated signal. As here shown, each device A is the well-known tuned reed alternator. Referring to alternator 13A, for example, the reference character 25 21 designates a reed which is caused to vibrate between terminals 22 and 23 by a control winding 24. In the deenergized condition, reed 21 does not connect with either terminal 22 or terminal 23 but does connect with a terminal 25. When energy is supplied to alternator 13A, winding 24 will attract reed 21 causing it to connect with terminal 23 and to move away from terminal 25, causing winding 24 to become deenergized. Upon the deenergization of winding 24, the resilience of reed 21 will cause it to move away from terminal 23 and to connect with terminal 22 as well as with terminal 25. The circuit for winding 24 will then be completed so that reed 21 again will go through the cycle of operation just described. Winding 24, therefore, will be repeatedly energized and deenergized as long 45 as energy is supplied to its control circuit. When reed 21 connects with terminal 23, current will be supplied to the right-hand portion of primary winding 19 of transformer 13N, and when reed 21 connects with terminal 22, current will then 50 be supplied in the opposite direction to the left-hand portion of primary winding 19. Alternating current, therefore, will be induced in secondary winding 20 of transformer 13N as long as alternator 13A is operating.

55 The alternator A for each of the other signals functions to supply alternating current to the associated transformer N in a manner similar to that described for alternator 13A.

Under normal conditions, that is, with the 60 stretch unoccupied, each relay H is energized in the normal direction and, therefore, each relay J also is energized. Relay 11H, for example, is energized in the normal direction by a circuit which passes over a path from terminal B of the 65 direct current source at signal 13, through front point of contact 26 of relay 13H, front contact 27 of relay 2TR, front contact 28 of relay 1TR, relay 11H, front contact 29 of relay 1TR, front contact 30 of relay 2TR, and front point of contact 31 of relay 13H to terminal C of the same source of energy. Relay 11J also is energized over a circuit which passes over the same path as just described for relay 11H except that front points of contacts 32 and 33 of relay 11H and 75 relay 11J are substituted for relay 11H.

When the relays H are energized in the normal direction and the associated relay J also is energized, the green lamp G of the upper unit U of the associated signal is energized to cause the display of a green light to indicate "proceed at normal speed." For example, the green lamp G of the upper unit U of signal 11 is energized by a circuit which passes over a path from terminal B through front point of contact 34 of relay 11J, front contact 35 of relay 11H, normal polar contact 36-37 of relay 11H, and lamp G to terminal C. 5

10 Each signal, therefore, under normal conditions, has its control relays H and J energized in such a manner as to cause the signal to display 15 the normal proceed indication.

I shall now assume that an eastbound train, that is, a train traveling from left to right, enters section W-X so that relay 1TR becomes released to cause the deenergization of relays 11H 20 and 11J.

When relay 11J becomes deenergized, the red lamp R of the upper unit U of signal 11 will be energized by a circuit which passes over a path from terminal B through back point of contact 25 34 of relay 11J and lamp R to terminal C. Signal 11, therefore, will display a red light to indicate "stop."

When the train enters section X-Y so that relay 3TR becomes released, relays 13H and 13J 30 will become deenergized. Relay 13J, however, due to its slow releasing characteristic, will not release immediately. In the meantime, a pickup circuit will be established for directional stick relay 13S. This circuit may be traced from terminal B through back contact 40 of relay 3TR, front point of contact 41 of relay 13J, and relay 13S to terminal C. When relay 13S becomes picked up, a stick circuit will be closed over a path which passes from terminal B through 40 back contact 40 of relay 3TR, front contact 42 of relay 13S, and relay 13S to terminal C. When relay 13J does become released, a second stick circuit will be established so that relay 13S will be maintained in its picked up condition as long 45 as relay 13J remains in its released condition, that is, as long as the train occupies section X-Y. The second stick circuit passes over a path from terminal B through back point of contact 41 of relay 13J, front contact 42 of relay S, and relay 50 13S to terminal C.

When relay 13S is picked up, alternator 13A will be energized over front contact 43 of relay 13S so that alternating current energy will be induced in secondary winding 20 of transformer 55 13N.

When both relays 13J and 13H are released and relay 13S is picked up, signal 13, of course, will indicate "stop", and the line conductors for the section W-X will be supplied with alternating 60 current so that primary winding 44 of transformer 11M will become energized when the train vacates section W-X. The circuit for transformer 11M passes over a path from one terminal of secondary winding 20 of transformer 13N 65 through front contact 45 of relay 13S, back point of contact 46 of relay 13J, back point of contact 26 of relay 13H, front contact 27 of relay 2TR, front contact 28 of relay 1TR, primary winding 44, resistor 11F, front contact 29 of relay 1TR, 70 front contact 30 of relay 2TR, back point of contact 31 of relay 13H, back point of contact 47 of relay 13J, and front contact 48 of relay 13S to the other terminal of secondary winding 20 of transformer 13N. When primary winding 44 of 75

transformer $11M$ is energized by alternating current, current will be induced in secondary winding 49 so that relay $11J$ will become energized over an easily traced circuit which includes the 5 back points of contacts 32 and 33 of relay $11H$.

When relay $11J$ is energized and relay $11H$ is deenergized, the yellow lamp Y of the upper unit U of signal 11 will be energized so that that 10 signal will display a single yellow light to indicate "approach next signal prepared to stop". The circuit for lamp Y may be traced from terminal B through front point of contact 34 of relay $11J$, back point of contact 50 of relay $11H$, and lamp Y to terminal C .

15 When the train departs from section $X-Y$ and enters section $Y-Z$, both relays $15H$ and $15J$ will become deenergized and relay $15S$ will become energized. Signal 15 , therefore, will indicate "stop" and the line conductors for the section $X-Y$ will be supplied with alternating current by alternator $15A$ in a manner similar to that just described for section $W-X$ so that relay $13J$ will become energized to cause signal 13 to display a single yellow light to indicate "approach 20 next signal prepared to stop".

When relay $13J$ becomes energized, relay $13S$ will become released so that energy will be disconnected from alternator $13A$, and the line conductors for the section $W-X$ will be supplied with 25 direct current in the reverse direction so that relay $11H$ will become energized in that direction. The circuit for relay $11H$ may be traced from terminal B at signal 13 , through front point of contact 47 of relay $13J$, back point of contact 31 of relay $13H$, front contact 30 of relay $2TR$, front contact 29 of relay $1TR$, relay $11H$, front contact 28 of relay $1TR$, front contact 27 of relay $2TR$, back point of contact 26 of relay $13H$, and front point of contact 46 of relay $13J$ to terminal C .

40 With relay $11H$ energized in the reverse direction, relay $11J$ also will become energized over front points of contacts 32 and 33 of relay $11H$, so that the yellow lamps Y of both the upper and lower units of signal 11 will be energized to cause signal 11 to display a yellow light above a yellow light to indicate "approach next signal at medium speed". The circuit for the lamp Y of the upper unit U of signal 11 may be traced from terminal B through front point of contact 34 of 45 relay $11J$, front point of contact 50 of relay $11H$, reverse polar contact $51-52$ of relay $11H$, and lamp Y to terminal C ; and the circuit for the lamp Y of the lower unit L may be traced from terminal B through front point of contact 34 of relay $11J$, front contact 35 of relay $11H$, reverse polar contact $36-53$ of relay $11H$, and lamp Y to terminal C .

When the train departs from section $Y-Z$ and enters the section immediately to the right of 60 location Z , both relays $17H$ and $17J$ will become deenergized. Signal 17 , therefore, will indicate "stop", alternator $17A$ will be energized over the back contact 54 of relay $17J$, and the line conductors for the section $Y-Z$ will be supplied with alternating current energy so that relay $15J$ will be energized over an easily traced circuit to cause signal 15 to display a single yellow light to indicate "approach next signal prepared to stop". 65 When relay $15J$ becomes energized, relay $15S$ will become released and relay $13H$ will become energized in the reverse direction over a circuit similar to that described for the reverse energization of relay $11H$ so that signal 13 will be caused to display a yellow light above a yellow 70

light to indicate "approach next signal at medium speed".

When relay $13H$ is energized, relay $11H$ will be energized in the normal direction over the previously traced normal circuit, and relay $11J$, similarly, will be energized over its previously traced normal circuit. 5

When relay 11 is energized in the normal direction, relay $11J$ also will be energized so that the green lamp G of signal 11 will be energized over its previously traced circuit to cause signal 11 to display the normal proceed indication. 10

Summing up thus far, it will be seen that when an eastbound train that has passed through the stretch occupies the section to the right of location Z , signal 17 will display a red light to indicate "stop" and the line conductors for the section $Y-Z$ will be supplied with alternating current, signal 15 will display a yellow light to indicate "approach next signal prepared to stop" and the line conductors for the section $X-Y$ will be supplied with direct current in the reverse direction, signal 13 will display a yellow light above a yellow light to indicate "approach next signal at medium speed" and the line conductors for the section $W-X$ will be supplied with direct current in the normal direction, and signal 11 will display a green light to indicate "proceed at normal speed". 15 20 25

It will be noted that relays H are provided with a retained neutral characteristic, that is, the front neutral contacts of these relays do not open during pole changing periods. This feature prevents tumble-down of the signal circuits to the rear during these periods. For example, when the train vacates the section to the right of location Z and has passed a predetermined point (not shown) in advance of the other end of the passing siding $P2$, relay $13H$, which has previously been energized in the reverse direction, will then become energized in the normal direction to cause signal 13 to then display the normal proceed indication. Since, however, the front points of contacts 26 and 31 of relay $13H$ do not become open during such pole changing periods, the energization of the line circuit for the section $W-X$ will not be disturbed. 30 35 40 45

It will be noted also that the relays J are provided with a slow releasing characteristic so that these relays will not become released during the time their control circuits are being transferred from the back points to the front points of the associated relay H . This feature prevents a momentary flash of the red lamp of the associated signal since such lamps are controlled by a back contact of the relays J and will become energized whenever the associated relay J is released. 50 55

With all the signals and associated apparatus in the normal condition as shown in the drawings, I shall next assume that a westbound train, that is, a train moving from right to left enters section $Y-Z$ so that relay $6TR$ becomes released to open the control circuits for the relays $15H$ and $15J$. With both relays $15H$ and $15J$ released, signal 15 will indicate "stop" and the line circuits for the section $X-Y$ will become deenergized to cause both relays $13H$ and $13J$ to become deenergized. With both relays $13H$ and $13J$ deenergized, signal 13 will indicate "stop" and the line circuits for the section $W-X$ will become deenergized to cause both relays $11H$ and $11J$ to become deenergized so that signal 11 will indicate "stop". It will be seen, therefore, that all signals governing movements towards the westbound train will indicate "stop". The directional 70 75

stick relays 15S and 13S cannot become picked up as the westbound train proceeds through the stretch since pickup circuits for the directional stick relays can become closed only if the associated relay J is picked up.

For governing westbound movements in the stretch between the passing sidings P1 and P2 I provide headblock signals 12 and 18 and intermediate signals 14 and 16. Although, in order to simplify the drawings, I have not shown full and complete circuits and control apparatus for the westbound signals, it is understood that these signals and associated apparatus will function in all respects in a manner similar to that described for the eastbound signals. In connecting up the westbound signals, only one additional line conductor will be required since one line conductor of the pair for eastbound signals may be used as a common conductor for both eastbound and westbound signals.

In order to illustrate how one alternator A and associated transformer N may be utilized for each pair of signals, I have shown the directional stick relays 14S and 16S for the intermediate signals 14 and 16, respectively, and the signal control relays 12J and 18J for the headblock signals 12 and 18, respectively. For example, it will be apparent that alternator 13A may be energized either over front contact 43 of relay 13S or front contact 55 of relay 14S. It will also be apparent that when relay 14S is energized so that its front contacts 55, 56, and 57 are closed, alternating current may be supplied to wires 58 and 59, which are here shown as a portion of the conductors extending to the rear of signal 14 for the control of signal 16.

In a similar manner, it will be obvious how alternating current may be supplied to the conductors extending to the rear of the headblock signals. For example, when relay 18J is deenergized so that back contacts 60, 61, and 62 are closed, alternator 17A will become energized so that wires 63 and 64, which are here shown as a portion of the conductors extending to the rear of signal 18, will be supplied with alternating current.

Although I have shown only two pairs of intermediate signals located between the ends of the passing sidings, it is understood that more or less than two pairs of intermediate signals may be provided if desired. Furthermore, each pair of signals may be staggered or may be located directly opposite one another as shown in the drawings.

From the foregoing description of the apparatus embodying my invention, it is apparent that I have provided a three-block, four-indication, system of absolute permissive block signaling wherein only three line conductors are required and wherein, although alternating current is required, no commercial source of alternating current need be available. My system is economical in current consumption for the operation of the alternators A, since these alternators are required to operate only when the stretch is occupied by a train.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track provided with a track circuit including a track

relay, a polarized relay for said section, means governed by traffic conditions in advance of said section for reversibly energizing said polarized relay, a neutral relay for said section which becomes energized whenever said polarized relay is energized, means governed by other traffic conditions in advance of said section for energizing said neutral relay independently of the energization of said polarized relay, a directional relay for said section governed by said neutral relay and by said track relay, and a signal control circuit governed by said directional relay.

2. In combination, a section of railway track provided with a track circuit including a track relay, a polarized relay for said section, means governed by traffic conditions in advance of said section for reversibly energizing said polarized relay, a neutral relay for said section which becomes energized whenever said polarized relay is energized, means governed by other traffic conditions in advance of said section for energizing said neutral relay independently of the energization of said polarized relay, a normally deenergized stick relay for governing a signal control circuit, a pickup circuit for said stick relay including a back contact of said track relay and a front contact of said neutral relay, a stick circuit for said stick relay including a back contact of said track relay and a front contact of said stick relay, and another stick circuit for said stick relay including its own front contact and a back contact of said neutral relay.

3. In combination, a section of railway track provided with a track circuit including a track relay, a pair of conductors each including a front contact of said track relay, means governed in accordance with traffic conditions in advance of said section for supplying said pair of conductors with direct current of one polarity or with direct current of the other polarity or with alternating current, a direct current polarized relay connected to said conductors, an asymmetric unit connected directly to said conductors over front contacts of said polarized relay or connected through a transformer to said conductors over back contacts of said polarized relay, a direct current neutral relay connected to said asymmetric unit, and a signal for said section controlled by said polarized and neutral relays.

4. In combination, a section of railway track provided with a track circuit including a track relay, a pair of conductors each including a front contact of said track relay, means governed in accordance with traffic conditions in advance of said section for supplying said conductors with direct current of one polarity or with direct current of the other polarity or with alternating current, a direct current polarized relay connected to said conductors, an asymmetric unit connected directly to said conductors over front contacts of said polarized relay or connected through a transformer to said conductors over back contacts of said polarized relay, a direct current relay connected to said asymmetric unit, a signal for said section including a first unit comprising a green and a red as well as a yellow lamp and a second unit comprising another yellow lamp, a circuit for said green lamp including a front contact of said neutral relay as well as a front neutral and a normal polar contact both of said polarized relay, a circuit for said red lamp including a back contact of said neutral relay, a circuit for the yellow lamp

- of the first unit including a front contact of said neutral relay and a back contact of said polarized relay, another circuit for said yellow lamp including a front contact of said neutral relay 5 and a front neutral as well as a reverse polar contact both of said polarized relay, and a circuit for said other yellow lamp including a front contact of said neutral relay as well as a front neutral and a reverse polar contact back of said polarized relay.
5. In combination, a forward section and a rear section of railway track, a first relay and a second relay, means governed in accordance with traffic conditions in advance of said forward section for energizing said first and second relays simultaneously or for energizing said second relay only, a directional relay controlled by said second relay and by traffic conditions in the forward section, a circuit governed by said directional relay when both said first and said second relays are deenergized, another circuit governed by said second relay when said first relay is deenergized, still another circuit controlled by said first relay, and traffic governing 10 means for the rear section governed by said three circuits.
6. In combination, a section of railway track, a polarized relay for said section, a neutral relay for said section, means including a directional relay controlled by traffic conditions in advance of said section for energizing said polarized relay in the normal direction and for simultaneously energizing said neutral relay or for energizing said polarized relay in the reverse direction and for simultaneously energizing said neutral relay or for energizing said neutral relay only or for deenergizing said neutral relay, and a signal for said section controlled by said two relays and capable of displaying a stop indication when said neutral relay is deenergized or a restrictive proceed indication when said neutral relay only is energized or one or the other of two different and successively less restrictive proceed indications according as said polarized relay is energized in the normal or reverse direction respectively provided said neutral relay also is energized.
7. In combination, a stretch of railway track having a forward and a rear signal associated therewith each governing traffic in the same direction and each capable of assuming a condition to indicate stop, approach, approach medium, or proceed, means effective only when the forward signal is in condition to indicate approach medium or proceed and the stretch between said signals is unoccupied for causing the rear signal to assume the condition to indicate proceed, means effective only when the forward signal is in condition to indicate approach and the stretch between said signals is unoccupied for causing the rear signal to assume the condition to indicate approach medium, a normally deenergized relay, means for energizing said relay when a train passes the forward signal provided said forward signal is then in condition to indicate approach, approach medium or proceed, means effective a predetermined time interval after such train passes the forward signal for causing that signal to assume the condition to indicate stop, means then effective to hold said relay energized, and means effective only when said relay is energized and the stretch between said signals is unoccupied for causing the rear signal to assume the condition to indicate approach.
8. In combination, a stretch of railway track
- having a forward and a rear signal each governing traffic in the same direction and each capable of assuming a condition to indicate stop, approach, approach medium or proceed, means effective when the stretch between said signals is unoccupied for causing the rear signal to assume the condition to indicate proceed provided the forward signal is then in condition to indicate either approach medium or proceed and for causing the rear signal to assume the condition to indicate approach medium provided the forward signal is then in condition to indicate approach, directional means which becomes energized when a train passes the forward signal provided that signal is then in condition to indicate approach, approach medium or proceed, means for causing said forward signal to assume the condition to indicate stop a predetermined time interval after such train passes the forward signal, means then effective to hold said directional means energized, and means effective only when said directional means is energized and the stretch between said signals is unoccupied for causing the rear signal to assume the condition to indicate approach.
9. In combination, a stretch of railway track having a forward and a rear signal each governing traffic in the same direction and each capable of assuming a condition to indicate stop, approach, approach medium or proceed, a pair of conductors for the rear signal governed by traffic conditions in the stretch between said signals, means for supplying said conductors with current of one character to cause the rear signal to assume the condition to indicate proceed when the forward signal is then in condition to indicate proceed or approach medium and for supplying said conductors with current of another character to cause the rear signal to assume the condition to indicate approach medium when the forward signal is in condition to indicate approach, directional means which means become energized when a train passes the forward signal provided that signal is then in condition to indicate approach, approach medium or proceed, means for causing the forward signal to assume the condition to indicate stop a predetermined time interval after such train passes the forward signal, means effective thereafter to hold said directional means energized, and means effective when said directional means is energized to supply said conductors with current of still a different character to cause the rear signal to assume the condition to indicate approach.
10. In combination, a stretch of railway track, a pair of conductors, directional means automatically controlled by the direction of traffic in said stretch, means including said directional means for successively supplying said conductors with three different forms of energy when and only when a train moves through said stretch in one direction, a signal for said stretch governing traffic moving in said one direction and capable of displaying three distinctive proceed indications, and control means selectively responsive to said three forms of energy for governing the three indications of said signal.
11. In combination, a stretch of railway track, a pair of conductors, directional means automatically controlled by the direction of traffic in said stretch, means including said directional means for successively supplying said pair of conductors with three different forms of current respectively when a train moves through said stretch in one direction but for disconnecting energy from said conductors when a train moves

through said stretch in the opposite direction, a signal for said stretch governing traffic moving in said one direction and capable of displaying a stop indication and three successively less restrictive proceed indications, and control means selectively responsive to the deenergized condition and the three energized conditions of said pair of conductors for governing the four indications of said signal.

12. In combination, a stretch of railway track, a pair of conductors, directional means automatically controlled by the direction of traffic in said stretch, means including said directional means for supplying said pair of conductors successively with alternating current, with direct current of one polarity and with direct current of the other polarity when a train moves through said stretch in one direction but for disconnecting energy from said conductors when a train moves through said stretch in the opposite direction, a signal for said stretch governing traffic moving in said one direction and capable of displaying a stop indication and three successively less restrictive proceed indications, and control means selectively responsive to the deenergized condition and the three energized conditions of said pair of conductors for governing the four indications of said signal.

13. A railway signal system for a stretch of railway track over which traffic moves in either direction comprising, signals at spaced intervals along said stretch for governing the movement of trains in both directions, each said signal capable of displaying a stop indication and three successively less restrictive proceed indications, a pair of conductors for each signal, control means for each signal receiving energy from the associated conductors and capable of assuming four distinctive conditions to control the four indications according as such conductors are deenergized or energized with three different characters of current respectively, directional means automatically controlled by the direction of traffic in said stretch, and means including said directional means effective when a train moves through said stretch in one direction to energize each pair of conductors for the signals governing traffic in said one direction with said three different characters of current successively but for deenergizing each pair of conductors for the signals governing traffic in the opposite direction.

14. In combination, a stretch of railway track over which traffic moves in either direction, said track stretch being divided into a plurality of successive block sections each having a signal governing movement of trains therein in one direction, each block section having associated therewith a pair of conductors and a fast acting relay governed by traffic conditions in said section, each of said sections having associated therewith a slow acting relay energized from the conductors for such section, each of said sections having associated therewith an alternating current supply device for converting direct current into alternating current and for supplying said alternating current to a circuit through which said current may be supplied to the conductors of the adjacent block section in the rear, each of said sections having associated therewith a directional relay controlled jointly by the associated fast and slow acting relays and controlling the circuit for supplying direct current to said alternating current supply device, each of said sections having means energized from the conductors for said section and controlling the sup-

ply of direct current to the conductors of the adjacent block section in the rear, each of said block sections also having control means associated therewith and controlling the signal for such section, said control means being energized from the conductors for such section and being selectively responsive to alternating and to direct current supplied to said conductors.

15. In combination, a stretch of railway track over which traffic moves in either direction, said track stretch being divided into a plurality of successive block sections each having a signal governing movement of trains therein in one direction, each block section having associated therewith a fast acting relay governed by traffic conditions in said section and a pair of conductors governed by said fast acting relay, each of said sections having associated therewith a slow acting relay energized from the conductors for such section, each of said sections having associated therewith an alternating current supply device for converting direct current into alternating current and for supplying said alternating current to a circuit through which said current may be supplied to the conductors of the adjacent block section in the rear, each of said sections having associated therewith a directional relay controlled jointly by the associated fast and slow acting relays and controlling the circuit for supplying direct current to said alternating current supply device, each of said sections having means energized from the conductors for said section and controlling the supply of direct current to the conductors of the adjacent block section in the rear, each of said block sections also having control means associated therewith and controlling the signal for such section, said control means being energized from the conductors for such section and being selectively responsive to alternating and to direct current supplied to said conductors.

16. In combination, a stretch of railway track over which traffic moves in either direction, said track stretch being divided into a plurality of successive block sections each having a signal governing movement of trains therein in one direction, each block section having associated therewith a pair of conductors and a fast acting relay governed by traffic conditions in said section, each of said sections having associated therewith a slow acting relay energized from the conductors for such section, each of said sections having associated therewith an alternating current supply device for converting direct current into alternating current and for supplying said alternating current to a circuit through which said current may be supplied to the conductors of the adjacent block section in the rear, each of said sections having associated therewith a directional relay controlled jointly by the associated fast and slow acting relays and controlling the circuit for supplying direct current to said alternating current supply device, said directional relay also controlling the circuit through which alternating current is supplied from said supply device to the conductors of the adjacent block section in the rear, each of said sections having means energized from the conductors for said section and controlling the supply of direct current to the conductors of the adjacent block section in the rear, each of said block sections also having control means associated therewith and controlling the signal for such section, said control means being energized from the conductors for such section and

- being selectively responsive to alternating and to direct current supplied to said conductors.
17. In combination, a stretch of railway track over which traffic moves in either direction, said track stretch being divided into a plurality of successive block sections each having a pair of conductors and a fast acting relay governed by traffic conditions in said section, each section having a signal capable of displaying a normal proceed indication and a plurality of restrictive proceed indications, each of said sections having associated therewith a first and a second control device energized from the conductors for the section and controlling the signal for such section, said first control device being responsive to the supply of direct current to said conductors and said second control device being responsive to the supply of alternating current to said conductors, each signal having associated therewith an alternating current supply mechanism operative on the supply of direct current thereto to supply alternating current to a circuit through which alternating current may be supplied to the conductors of the adjacent block section in the rear, each section having a directional relay controlled jointly by the fast acting relay and one of the control devices for the signal for such section, the directional relay controlling the circuit for supplying direct current to the associated alternating current supply mechanism, the second control device being operative when energized to condition the signal to display a restrictive proceed indication, the first control device being operative alone when energized to condition the signal to display its normal proceed indication, the second control device controlling a circuit for supplying direct current to the conductors of the adjacent block section in the rear.
18. In combination, a stretch of railway track over which traffic moves in either direction, said track stretch being divided into a plurality of successive block sections each having a pair of conductors and a fast acting relay governed by traffic conditions in said section, each section having a signal capable of displaying a normal proceed indication and a plurality of restrictive proceed indications, each of said sections having associated therewith a first and a second control device energized from the conductors for the section and controlling the signal for such section, said first control device being responsive to the supply of direct current to said conductors and said second control device being responsive to the supply of alternating current to said conductors, each signal having associated therewith an alternating current supply mechanism operative on the supply of direct current thereto to supply alternating current to a circuit through which alternating current may be supplied to the conductors of the adjacent block section in the rear, each section having a directional relay controlled jointly by the fast acting relay and one of the control devices for the signal for such section, said one of the control devices and the directional relay jointly controlling the circuit for supplying direct current to the alternating current supply mechanism for such section, the second control device being operative when energized to condition the signal to display a restrictive proceed indication, the first control device being operative alone when energized to condition the signal to display its normal proceed indication, the second control device controlling a circuit for supplying direct current to the conductors of the adjacent block section in the rear.

cuit for supplying direct current to the conductors of the adjacent block section in the rear.

19. In combination, a stretch of railway track over which traffic moves in either direction, said track stretch being divided into a plurality of successive block sections each having a pair of conductors and a fast acting relay governed by traffic conditions in said section, each section having a signal capable of displaying a normal proceed indication and a plurality of restrictive proceed indications, each of said signals having associated therewith a first and a second control device energized from the conductors for the section and controlling the signal for such section, said first control device being responsive to the supply of direct current to said conductors and said second control device being responsive to the supply of alternating current to said conductors, each signal having associated therewith an alternating current supply mechanism operative on the supply of direct current thereto to supply alternating current to a circuit through which alternating current may be supplied to the conductors of the adjacent block section in the rear, each section having a directional relay controlled jointly by the fast acting relay and one of the control devices for the signal for such section, the directional relay controlling the circuit for supplying direct current to the alternating current supply mechanism for such section, said first and second control devices and the directional relay jointly controlling the circuit for supplying direct current to the supply mechanism for said section, the second control device being operative when energized to condition the signal to display a restrictive proceed indication, the first control device being operative alone when energized to condition the signal to display its normal proceed indication, the second control device controlling a circuit for supplying direct current to the conductors of the adjacent block section in the rear.

20. In combination, a stretch of railway track over which traffic moves in either direction, said track stretch being divided into two adjacent block sections including a forward and a rear block section, each of said block sections having a signal governing movement of trains therein in one direction, each of said block sections having a pair of conductors governed by traffic conditions in said section, means energized from the conductors of the forward block section for controlling the signal for such section and for controlling a circuit through which direct current may be supplied to the conductors of the rear block section, the forward section having associated therewith a fast acting relay governed by traffic conditions in said forward section and a slow acting relay energized from the conductors for such section, the forward section also having associated therewith an alternating current supply device for converting direct current into alternating current and for supplying such alternating current to a circuit through which current may be supplied to the conductors of the rear block section, said forward block section having associated therewith a directional relay controlled jointly by said fast and slow acting relays and controlling the circuit for supplying direct current to said supply device, and means selectively responsive to alternating and direct current supplied to the conductors of the rear section for governing the signal for said rear section.

21. In combination, a stretch of railway track over which traffic moves in either direction, said

- track stretch being divided into a plurality of successive block sections each having a signal governing movement of trains therein in one direction, each of said block sections having a pair of conductors and a fast acting relay governed by traffic conditions in said section, each of said block sections having a pair of control relays energized from the conductors for such section and controlling the signal for such section, one 5 of said relays being responsive to direct current supplied to said conductors, the other of said relays being responsive to alternating current supplied to said conductors, one of said relays being slow acting, each of said block sections having associated therewith an alternating current supply 10 device for converting direct current into alternating current and for supplying such current to a circuit through which current may be supplied to the conductors of the adjacent block section 15 in the rear, each of said block sections having associated therewith a directional relay controlled jointly by the associated fast acting relay and the slow acting one of the control relays, said directional relay controlling the supply of direct current 20 to the supply device for such block section, and means controlled by one of the control relays 25 for each block section for supplying direct current to the conductors of the adjacent block section in the rear.
22. In combination, a stretch of railway track over which traffic moves in either direction, said track stretch being divided into a plurality of successive block sections each having a signal governing movement of trains therein in one direction, each of said block sections having a pair of conductors and a fast acting relay governed by traffic conditions in said section, each of said block sections having a pair of control relays energized from the conductors for such section and 30 controlling the signal for such section, one of said relays being responsive to direct current supplied to said conductors, the other of said relays being responsive to alternating current supplied to said conductors, one of said relays being slow acting, each of said block sections having associated therewith an alternating current supply device for converting direct current into alternating current and for supplying such current to a circuit through which current may be supplied to the conductors of the adjacent block section 35 in the rear, each of said block sections having associated therewith a directional relay controlled jointly by the associated fast acting relay and the slow acting one of the control relays, said directional relay controlling the supply of direct current to the supply device for such block section, and means controlled by both of said control relays 40 for each block section for selectively supplying direct current of one polarity or the other to the conductors of the adjacent block section in the rear.
23. In combination, a stretch of railway track over which traffic moves in either direction, said track stretch being divided into a plurality of successive block sections each having a signal governing movement of trains therein in one direction, each of said block sections having a pair of conductors and a fast acting relay governed by traffic conditions in said section, each of said block sections having a pair of control relays energized from the conductors for such section and controlling the signal for such section, one of said relays being responsive to direct current supplied to said conductors, the other of said relays being responsive to alternating current supplied to said conductors, one of said relays being slow acting, each of said block sections having associated therewith an alternating current supply device for converting direct current into alternating current and for supplying such current to a circuit through which current may be supplied to the conductors of the adjacent block section in the rear, each of said block sections having associated therewith a directional relay controlled jointly by the associated fast acting relay and the slow acting one of the control relays, said directional relay controlling the supply of direct current to the supply device for such block section, and means controlled by both of said control relays for each block section for supplying direct current to the conductors of the adjacent block section in the rear.
24. In combination, a section of railway track provided with a pair of conductors and a fast acting relay governed by traffic conditions in said section, means governed by traffic conditions in advance of said section for supplying direct and alternating current to said conductors, a first and a second control relay for said section energized from said conductors, said first control relay being energized whenever said conductors are energized with direct current, said second control relay being energized whenever said conductors are energized with alternating current and whenever said first control relay is energized, one of said control relays being slow acting, a directional relay controlled jointly by said fast acting relay and the slow acting one of the control relays, and a signal control circuit controlled by said directional relay.
25. In combination, a section of railway track provided with a pair of conductors and a fast acting relay governed by traffic conditions in said section, means governed by traffic conditions in advance of said section for supplying direct and alternating current to said conductors, a first and a second control relay energized from said conductors, said first control relay being responsive to the supply of direct current to said conductors, said second control relay being responsive to the supply of alternating current to said conductors, one of said relays being slow acting, a directional relay controlled jointly by said fast acting relay and the slow acting one of said control relays, and a signal control circuit controlled by said directional relay.
